(57) **CLAIM**

The ornamental design for a camera tripod, as shown and described.

DESCRIPTION

FIG. 1 is a front-left-upper isometric view of a camera tripod showing our new design in a first configuration.

FIG. 2 is a lower-right-upper isometric view of the camera tripod in the first configuration.

FIG. 3 is a front view of the camera tripod in the first configuration.

FIG. 4 is a right-side view of the camera tripod in the first configuration.

FIG. 5 is a back view of the camera tripod in the first configuration.

FIG. 6 is a left-side view of the camera tripod in the first configuration.

FIG. 7 is a top view of the camera tripod in the first configuration.

FIG. 8 is a bottom view of the camera tripod in the first configuration.

FIG. 9 is a back view of the camera tripod in a second configuration.

FIG. 10 is a front-left-upper isometric view of the camera tripod in a third configuration.

FIG. 11 is a top view of the camera tripod in the third configuration; and,

FIG. 12 is a right-side view of the camera tripod in the third configuration.

Broken lines shown in the FIGURES depict boundary lines and additional features of the camera tripod. However, no
